(57) CLAIM

The ornamental design for a tissue box, as shown and described.

DESCRIPTION

FIG. 1 is a perspective view of a tissue box according to our new design.

FIG. 2 is a front view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The tissue box is shown with symbolic breaks. The appearance of any portion of the article between the break lines forms no portion of the claimed design.

The evenly broken lines are shown for the purpose of illustrating parts of the article that form no part of the claimed design. The broken lines consisting of dot-dash lines are boundary lines that show that the claimed design extends to, but does not include, the boundary lines.

The Kleenex logo shown in dashed lines in the drawings is a registered trademark of Kimberly-Clark Worldwide, Inc. and forms no part of the claimed design.
